UNITED STATES PATENT OFFICE.

JAMES C. SUYDAM, OF EDENTON, NORTH CAROLINA.

STEAM-GENERATOR.

No. 823,230.

Specification of Letters Patent.

Patented June 12, 1906.

Application filed February 3, 1906. Serial No. 299,353.

To all whom it may concern:

Be it known that I, JAMES C. SUYDAM, a citizen of the United States, residing at Edenton, in the county of Chowan and State of North Carolina, have invented new and useful Improvements in Steam-Generators, of which the following is a specification.

My invention pertains to steam-generators; and it contemplates the provision of a compact sectional generator susceptible of being easily repaired and constructed with a view of quickly generating steam and withstanding the usage to which the steam-generators of motor-vehicles, fire-engines, and the like are ordinarily subjected.

With the foregoing in mind the invention will be fully understood from the following description and claims when the same are considered in connection with the accompanying drawings, forming part of this specification, in which—

Figure 1 is a vertical section of the generator constituting the present embodiment of my invention with some of the parts in elevation. Fig. 2 is a horizontal section taken through the steam-chamber of the generator in the plane indicated by the line 2 2 of Fig. 1, and Fig. 3 is a horizontal section taken in the plane indicated by the line 3 3 of Fig. 1 looking downwardly.

Similar letters designate corresponding parts in all of the views of the drawings, referring to which—

A is the lower section of my novel generator, which is preferably, though not necessarily, circular in horizontal section and is designed to contain in its lower portion a firebox and a hydrocarbon-burner or any other suitable means for affording the heat necessary to generate steam. Such heat-affording means forms no part of my invention, and I have therefore deemed it unnecessary to illustrate the same.

The lower section A is provided with a door-opening *a* and a door *b* to permit of access being readily gained to the heat-affording means, and said section is preferably made up of an inner wall *c*, an outer wall *d*, connected by stay-bolts *e* to the inner wall *c* and extending slightly above said inner wall, as indicated by *f*, for a purpose presently set forth, and lower and upper rings *g* and *h*, interposed and secured between the walls *c* and *d*, so as to form an annular water-leg *B*. At the points shown in Figs. 1 and 3 the lower section A is provided with sleeves *k*, which

extend through the inner and outer walls *c* and *d* and the water-leg *B* and are designed to carry or contain pipes, presently described.

C is the upper section of the generator, in which the steam-chamber *D* is contained. The said upper section C comprises a side wall or shell *l*, lower and upper heads *m* and *n*, flanged and riveted to the side wall or shell, the rivets complementary to the lower head *m* having their outer heads countersunk, as shown in Fig. 1, for a purpose which will presently appear, and a plurality of flues *p* for smoke and other products of combustion, extending between and through both of the heads *m* and *n* and supporting and staying the same. The lower end of the upper section C is set within the extended portion *f* of the lower section A, and packing *r*, of asbestos or other suitable material, is interposed between the two to prevent the escape of flames through the joint. The two sections A and C are detachably connected together by the opposed lugs *s* thereon and the bolts and nuts. At its upper end the upper section C is equipped with a loop *t*, preferably connected through stud-bolts, by which it may be lifted from the lower section A.

E is a stand-pipe carried by and depending from the lower head of the section C. The said pipe is exteriorly threaded at *u* to engage the correspondingly-threaded opening *v* in the lower head of section C, and it is provided at its upper end with a threaded ring *w*, which is arranged on and connected to the head *m* and is preferably, though not necessarily, provided with a plurality of radial apertures *x*, registered with apertures *x'* in the stand-pipe and designed to conduct water from the interior of the stand-pipe and distribute such water over the lower head of the steam-chamber. The stand-pipe being threaded into head *m* and the ring *w* being in chamber *D* assures the joint being water and steam tight.

Extending longitudinally from the lower end of the stand-pipe E and through the center of said stand-pipe to the upper head *n* of the section C is a flue *F*, which is fixed to the stand-pipe and the upper head *n* and is open at its lower and upper ends, so as to assist in conveying the products of combustion from the combustion-chamber and utilizing the heat given off by such products to convert the water into steam. The flue *F* assists the flues *p* in supporting and lending strength to the heads *m* and *n* of section C, as do also the

stay-rods *y*, which are grouped about the flue *F* and are interposed between and connected to the lower and upper heads, as shown in Figs. 1 and 2.

5 G G are pipes arranged outside the sections *A* and *C* and connecting the water-leg *B* and the steam-chamber *D*. These pipes respectively comprise lower and upper sections and unions detachably connecting said sections, and hence it will be apparent that when the boiler is set up ready for use said pipes will assist in the circulation of water from one section of the generator to the other, and yet when it is desired to separate the sections of 10 the generator the sections of the pipes may be expeditiously and easily disconnected to permit of such separation.

H H are coils of pipe connected at their upper ends to the steam-chamber *D* and at 15 their lower ends to the stand-pipe *E* in the manner shown in Fig. 1. These coils *H* are substantially of the same height as the stand-pipe *E* and are arranged in two (more or less) 20 circular series, as illustrated, with a view of utilizing the heat given off by the products of 25 combustion to the best advantage. The said coils *H* by virtue of their pendent position relative to the steam-chamber *D* are always occupied by water and permit free 30 circulation of water, and consequently it will be apparent that there is no liability of the 35 said coils being burned notwithstanding their direct exposure to the fire.

I I, Fig. 3, are pipes for the circulation of 40 water interposed between and connecting the lower portion of the stand-pipe *E* and portions of the water-leg *B* at opposite sides of the doorway *a*, and J and K, Figs. 1 and 3, 45 are pipes connected to the lower portion of the stand-pipe *E* and extending through the before-described sleeves *k* and provided outside said sleeves with washers *z*, designed to prevent the escape of flames and heat. The pipe *J* is provided at a point outside the section *A* with a cock *a'*, designed for use in removing collected sediment from the stand-pipe *E*, and it is also provided at a point between the cock *a'* and the section *A* with a 50 depending branch pipe *b'*, which is connected 55 at its lower end to a pipe *c'*, which in turn is connected to the water-leg *B* and is provided on its outer portion with a cock *d'*, designed to be opened when it is necessary to remove collected sediment from the water-leg. The 60 pipe *K* is provided outside of the section *A* with a branch *e'*, which is connected to the water-leg *B* and is designed to be connected to an injector or other means (not shown) for supplying the generator with water.

65 From the foregoing description the general operation of my novel generator will be fully understood, and such operation need not, therefore, be entered into in detail. It will also be apparent from the foregoing that my 70 novel generator is possessed of a large heating

surface for the rapid generation of steam and is so constructed as to assure equal expansion of all of its parts. It will further be apparent that the capacity of the chamber *D* is sufficient to prevent rapid evaporation in the 75 event of the water getting low and that by reason of the lower and upper sections being separable access may be readily gained to all of the interior parts to facilitate repair or replacing of the same.

75 While I have described the present embodiment of my invention in detail with a view of imparting a definite understanding of all of its parts, I desire it distinctly understood that in practice such changes or modifications may be made as fairly fall within the scope of my invention as claimed. I also desire to make it plain that in practice the generator is designed to be arranged in a casing compatible with its proper operation. Such 80 casing, however, forms no part of my invention, and I have therefore deemed it unnecessary to illustrate the same.

Having described my invention, what I claim, and desire to secure by Letters Patent, 90 is—

1. A steam-generator comprising a lower section forming a water-leg, an upper section 95 removably arranged on the lower section and forming a steam-chamber, means detachably connecting the lower and upper sections, exteriorly arranged, separable water-circulating connections intermediate the water-leg and the steam-chamber, and pendent water-holding means connected to and disposed below the steam-chamber and also connected with the water-leg.

2. A steam-generator comprising a lower section having an inner wall, an outer wall 100 extending above the inner wall, and rings interposed and secured between said walls, in combination with an upper section set within the extended portion of the outer wall of the lower section, packing interposed between the adjacent portions of the sections, opposed lugs on the lower and upper sections, and means detachably connecting the said opposed lugs.

3. In a steam-generator the combination of a lower section having an inner wall, an 115 outer wall extending above the inner wall and rings interposed and secured between said walls to form a water-leg, an upper section set within the extended portion of the outer wall of the lower section and forming a steam-chamber, water-circulating connections intermediate the water-leg and the steam-chamber, pendent water-holding means connected to and disposed below the steam-chamber and also connected with the 120 water-leg, packing interposed between the adjacent portions of the lower and upper sections, opposed lugs on the said sections, and means detachably connecting the said lugs.

4. A steam-generator comprising a water- 130

leg surrounding a combustion-chamber, a steam-chamber disposed above the water-leg and combustion-chamber and having a plurality of flues for products of combustion 5 extending between its lower and upper heads, direct connections for the circulation of water between the water-leg and the steam-chamber, a central stand-pipe communicating with the steam-chamber and depending from the lower head thereof, a flue extending through said stand-pipe and steam-chamber, coils of pipe grouped in the combustion-chamber around the stand-pipe and connected at their upper ends to the steam-chamber and at their lower ends to the stand-pipe, connections intermediate the stand-pipe and the water-leg, and means for supplying the generator with water.

5. A steam-generator comprising a water-leg 20 surrounding a combustion-chamber, a steam-chamber disposed above the water-leg and combustion-chamber and having a plurality of flues extending between its lower and upper heads, direct water-conduits intermediate the water-leg and the steam-chamber, a central stand-pipe extending through and depending from the lower head of the steam-chamber and having a ring resting on and connected to said head of the 25 chamber and also having passages in its ring for distributing water over the lower head of the steam-chamber, a flue extending through the said stand-pipe and the steam-chamber, coils of pipe grouped in the combustion-chamber around the stand-pipe and connected at their upper ends to the steam-chamber and at their lower ends to the lower portion of the stand-pipe, direct connections 30 intermediate the stand-pipe and the water-leg, a pipe extending from the stand-pipe through the water-leg and having a blow-off cock and also having a branch pipe connected with the water-leg and equipped with

a blow-off cock, and a second pipe connected to the stand-pipe and extending through the water-leg and connected to said leg from the outside and adapted to be connected with means for supplying the generator with water.

6. In a steam-generator, the combination of a combustion-chamber, a steam-chamber disposed above the combustion-chamber, and a stand-pipe extending through an opening in the lower head of the steam-chamber and depending in the combustion-chamber and having a ring at its upper end resting on the head of the steam-chamber and also having lateral passages in said ring for distributing water from its interior over the lower head of the steam-chamber and means connecting said ring and head.

7. In a steam-generator, the combination of a combustion-chamber, a steam-chamber disposed above the combustion-chamber, a central stand-pipe open at its upper end and extending through an opening in the lower head of the steam-chamber and depending in the combustion-chamber and having a ring at its upper end resting on the lower head of the steam-chamber and also having lateral passages in its ring for distributing water from its interior over the lower head of the steam-chamber, means connecting said ring and head, and one or more circular series of pipe-coils arranged in the combustion-chamber around the stand-pipe; the said coils being connected at their upper ends to the steam-chamber and at their lower ends to the lower portion of the stand-pipe.

In testimony whereof I have hereunto set my hand in presence of two subscribing witnesses.

JAMES C. SUYDAM.
